UNITED STATES PATENT OFFICE.

ROBERT R. GRAF, OF BALTIMORE, MARYLAND, ASSIGNOR OF TWO-THIRDS TO WILLIAM B. KRAUSE AND POTTHAST BROTHERS, OF BALTIMORE, MARYLAND.

REFRIGERATOR.

SPECIFICATION forming part of Letters Patent No. 757,911, dated April 19, 1904.

Application filed December 21, 1903. Serial No. 186,026. (No model.)

To all whom it may concern:

Be it known that I, ROBERT R. GRAF, a citizen of the United States, residing at Baltimore, in the State of Maryland, have invented 5 new and useful Improvements in Refrigerators, of which the following is a specification.

This invention has relation to that class of refrigerators or refrigerating-cabinets that are designed generally for use in the culinary 10 department of a household, though it will appear from the description hereinafter given that they may be employed elsewhere.

It is the purpose of the invention to provide an improved article of the character mentioned 15 that may be readily constructed and used and that will be efficient in the cooling of drinking-water and in the preservation of articles of food and other things stored therein.

To these ends the invention consists of the 20 refrigerator or cabinet and to combinations of parts and features thereof, as is hereinafter more fully set forth in connection with the accompanying drawing, forming a part of this specification, in which the figure of the 25 drawing is a central vertical sectional view of my improved refrigerator.

Similar figures of reference designate similar parts or features, as the case may be, wherever they occur.

In the drawing, 1 designates the walls or 30 casing of the cabinet, which may be of any suitable construction and which may be provided on top with a lid 2 or other opening means whereby access may be gained to the ice-receiving chamber 3 of dish-like form, having a wall or partition 4 upon a supporting plate or shelf 4', in which the ice may rest. Below the partition 4 of the ice-chamber is another supplementary partition 6 of a form 35 similar to the partition 4, and both partitions are supported by flanges 3' and 6', respectively resting upon ledges formed by the annular ring 7, secured to the inner sides of the wall 1 or in any other suitable way, the entire arrangement being such as to leave a space 8 between the partitions 5 and 6. Below the bottom 4', upon which the ice rests, is shown an-

other corrugation and perforated bottom 4''. Both bottoms 4' and 4'' are merely removable sheet-iron or galvanized plates of metal, so 50 that either may be used to support the cake of ice, the other being removed. If the cake should be thick, so that greater space should be needed between the ice-support and lid, the lower support or bottom 4'' may be used, or 55 if a thinner cake should be left in the ice-chamber in order to get at it readily the upper shelf may be employed. The two shelves are provided as a matter of mere convenience. For that matter one ice-support may be sufficient. 60

A hollow standard 9 is supported in the center of the cabinet, and a drain-pipe 10 is arranged in the standard and leads out through the partition of the cabinet, as is clearly shown.

The partition 5 has a stem-like opening 11 65 in its central lower part which fits in the top of the pipe 10, and the central lower part of the partition 6 is provided with a stem-like opening 12, which fits in the upper part of the standard 9. 70

A coil of pipe 13 is arranged between the two partitions 5 and 6 and at its upper end is provided with a funnel 14, arranged outside of the walls 1, into which drinking-water may be poured, and at its lower end is a water-receiver 15, having a spigot 16, extending outside, through which the water may be drawn. 75

It will be understood that the ice and the water dripping therefrom and running down through the perforations 5' on the water-coil 80 13 will keep the drinking-water cool and that the waste water will run off through the pipe 10 and its escape attachment, cooling the hollow standard and through it assisting to cool the interior of the cabinet. 85

17 designates rings adapted to be slipped upon the hollow standard 9 and to be fixed in place thereon by set-screws 18, as shown. 19 designates collars adapted also to be slipped upon the hollow standard and to rest upon the 90 fixed rings 17 and, if need be, turn thereon. The collars 19 have formed therein sockets 20, into which fit the angular inner ends 21 of the arms 22, which are recessed hori-

zontally, as at 23, to receive the bails 24 of the ice-baskets 25, adapted to have placed in them lumps of ice to cool anything placed therein and to assist in cooling the interior 5 of the cabinet.

The bails 24 of the ice-baskets may be slipped over the upwardly-projecting end 28 of the arm 22 and into the recess 23, said projection or other means of suitable character preventing the bails from accidentally slipping off the free ends of the arms.

29 designates shelves, in the present instance shown as of segmental form, which at their meeting edges are offset in opposite directions, as shown at 30, to preserve an even or smooth upper surface, said shelves being perforated, as at 31, and adapted to rest upon the arms 22. By the means described the cool air in the cabinet can circulate freely 20 therethrough, and all of the parts may be readily removed for the purpose of cleaning or for other purposes.

By the construction described a refrigerator and culinary cabinet is provided which is 25 very convenient in use, readily kept clean, and is so arranged that drinking-water may be supplied to and drawn from it with convenience also. When the ice in the ice-chamber is not sufficient to refrigerate to the desired degree, smaller pieces may be placed in 30 the ice-baskets to cool food placed on the shelves above or even in the ice-baskets.

By making the bottoms of concave form sheets for forming rests for the ice may be 35 made of various sizes and on being placed therein will be brought nearer to or farther from the bottom of the ice-chamber, as will be readily understood. Besides all of the drip

water will be guided to the hollow central standard to run down the same.

40

I claim—

1. A culinary cabinet or refrigerator embodying in its construction an ice chamber or receptacle having a partition of substantially concave form, a shelf supported thereby upon 45 which the ice may rest, a supplementary partition, also of substantially concave form below the first-named partition of the ice-chamber, a central hollow standard with which the supplementary partition communicates, a pipe 50 in the hollow standard with which the concave partition of the ice-chamber communicates, said pipe being provided with an offtake for the drip water, a coil of pipe between the said two partitions to receive drinking-water, 55 means for filling the said pipe and for draining the water off therefrom.

2. In a culinary refrigerating-cabinet, the combination, with the ice-chamber and its concaved or dish-shaped partition, and a shelf supported by the said partition, of a similarly-shaped supplementary partition below the partition of the ice-chamber, a coil of pipe between said partitions, means whereby water may be poured into said pipe and allowing it to be 65 cooled, and means extending outside of the cabinet for drawing off the cooled drinking-water.

In testimony whereof I have signed my name to this specification in the presence of two sub- 70 scribing witnesses.
